H. T. HUGHES

PLUG INSERTING TOOL

Filed May 10, 1926

Fig. 1

UNITED STATES PATENT OFFICE.

HUGH T. HUGHES, OF CLEVELAND, OHIO, ASSIGNOR, BY MESNE ASSIGNMENTS, TO
EDWARD HAINKE, OF GRAND RAPIDS, MINNESOTA.

PLUG-INSERTING TOOL.

Application filed May 10, 1926. Serial No. 107,977.

The objects of the invention are to provide efficient and convenient means for inserting a rubber patching plug in a puncture or opening in a pneumatic tire or tube for an automobile wheel. Such casings are constructed of alternate layers of fabric and rubber or rubber compound and hence are impervious to ordinary instruments, but by means of the improved instrument the rubber plug can be inserted or drawn through an opening in the densest substances.

The instrument comprises a needle shaped metal tube longitudinally slotted at its inner end to make the sides thereof compressible to engage with the stem of the plug and having a pointed outer head or extremity and provided with an annular shoulder or other engaging means, adjacent to the pointed end, which can be engaged by a suitable tool to pull the instrument while the plug is grasped thereby forcibly through the casing, thus overcoming the resistance to its passage.

The invention is exemplified in the accompanying drawings, hereinafter more fully described and specifically pointed out in the claims.

In the accompanying drawings, Fig. 1 is a transverse section of a casing showing the instrument in use and one form of an additional tool employed to pull it through the casing.

Fig. 2 is a longitudinal section showing another form of the tool grasping instrument.

Fig. 3 is a side elevation of the same.

Fig. 4 is a perspective of the same;

Fig. 5 is a side elevation, and

Fig. 6 is a plan of the grasping instrument shown in Fig. 1;

Fig. 7 is a transverse section of the inserting tool;

Figs. 8 and 9 are plan and edge views of a simple form of grasping instrument.

In these views A is the casing, B is a needle shaped instrument having a tubular longitudinally slotted inner end C in which the rubber plug T is inserted and a pointed outer end D. Adjacent to this end, the instrument is provided with engaging means such as an annular shoulder E upon the head shown in Figs. 1 and 2 and a tool G may be provided to engage with this shoulder to

draw the instrument through the casing. In one form of tool lugs G', G', are engaged with this shoulder to draw the instrument and plug through the puncture while the stem T of the plug is held between the arms of the slotted end C of the instrument as shown in Fig. 1.

In Figs. 2 and 3 a hook shaped draw instrument H is shown in which a keyhold shaped slot I is formed and the enlargement I' through which the head is inserted is positioned upon the side of the hook, thus making it impossible for the head of the inserting instrument to be withdrawn when in use.

In Figs. 8 and 9 a simple yoke J is shown as a draw tool, showing a transverse slot K therein open on one side. This yoke is conveniently shaped to be grasped by the hand and the back of the tool G is inserted in the slot.

Having described the invention, what I claim as new and desire to secure by Letters Patent is:

1. An instrument for inserting a tire plug consisting in, a tapered, hollow body having a compressible inner end, and provided with a pointed head at its outer end.

2. An instrument for inserting a tire plug consisting in, a tapered, hollow body having a compressible inner end, and having a pointed head at the outer end, the base of said head providing an annular shoulder adjacent to said outer end.

3. An instrument for inserting a tire plug consisting in, a tapered, hollow body pointed at the outer end and having an annular shoulder adjacent to said outer end.

4. An instrument for inserting a tire plug consisting in, a tapered, hollow body pointed at the outer end and having an annular shoulder adjacent to said outer end, and a gripping device for engaging with said shoulder to draw said instrument through said tire.

5. A tire repairing device comprising a needle having a hollow longitudinally split portion at one end thereof, a sharp head providing a shoulder at the other end of the needle, and a holder adapted to engage said shoulder.

6. A tire repairing device comprising a needle having a hollow longitudinally split

portion at one end thereof and a portion tapering toward the other end of the needle, a sharp head providing a shoulder at the outer end of said tapering portion, and 5 a holder adapted to engage said shoulder.

7. A tire repairing device comprising a needle having a hollow longitudinally split portion at one end thereof, a sharp head

providing a shoulder at the other end of the needle, and a bar containing a longitudinal 10 slot enlarged at one portion thereof to permit passage of said head.

In testimony whereof I hereunto affix my signature.

HUGH T. HUGHES.
